ATTORNEYS

UNITED STATES PATENT OFFICE.

LOUIS P. TERHAAR, OF NEW YORK, N. Y., ASSIGNOR OF ONE-THIRD TO HARRY KUTSCHER, OF NEW YORK, N. Y.

UNCHANGEABLE MOTOR NUMBER.

Application filed August 7, 1922. Serial No. 580,242.

To all whom it may concern:

Be it known that I, LOUIS P. TERHAAR, a citizen of the United States, and a resident of the city of New York, borough of Manhattan, in the county and State of New York, have invented a new and Improved 5 Unchangeable Motor Number, of which the following is a full, clear, and exact description.

10 This invention relates to legends or numbers for motors and particularly to an improved legend for use on automobile motors, the object being to provide a construction which cannot be changed or removed 15 without detection.

Another object of the invention is to provide a member with a number or legend thereon so constructed and connected with part of an engine that it cannot be changed 20 or mutilated without such fact being readily observed.

A still further object of the invention is to provide a number plate for engines which may be readily placed in position but which 25 cannot be removed or changed without breaking.

In the accompanying drawing—

Figure 1 is a fragmentary elevation of 30 part of an engine casing with an embodiment of the invention applied thereto.

Figure 2 is a sectional view through Figure 1 approximately on line 2—2.

Figure 3 is a mold for molding a glass body around the legend or number plate 35 shown in Figure 1.

Figure 4 is a sectional view through Figure 3 approximately on line 4—4.

Figure 5 is a perspective view of one of the end blocks shown in Figure 3.

40 Figure 6 is a sectional view through a conventional mold with the number plate and its surrounding body in position ready for the metal to be poured into the mold to provide the desired casting for the engine.

45 Figure 7 is an edge view on a reduced scale of a sand core and plate embodying certain features of a modified form of the invention to that shown in Figure 1.

Referring to the accompanying drawing 50 by numerals, 1 indicates part of the casing of an engine, said casing being provided with a depression 2 filled with glass or other fragile material 3 which is sufficiently transparent to permit a person to see the num-

bers or other legend on the strip of metal 4. 55 The number or legend strip 4 is preferably of some good quality of metal and has the ends imbedded in the casing 1. The number plate 4 may be connected with any part of the engine casing but preferably with the 60 crank casing as this part of the casing is probably the most difficult to replace by an unauthorized person.

In providing a construction as shown in Figures 1 and 2, the number is clearly visible but access thereto cannot be had unless the glass filler or body 3 is broken. Also, by reason of the imbedding of the ends of the plate 4 a new plate cannot be substituted without detection. The construction 70 shown in Figures 1 and 2 may be provided in several ways. Figures 3 to 6 inclusive, show molds for securing the result shown in Figures 1 and 2. In these figures it will be observed that member 5 is a mold having 75 a recess 6, said mold having upstanding end walls 7 and 8 on which the mold blocks 9 are mounted, said mold blocks being as shown in Figures 4 and 5, namely, with a recess 10 on the under face whereby an 80 opening is provided for the plate 4. When the mold 5 is in use, the plate 4 is mounted in the recesses 10 and extends entirely across the recess 6 in the mold 5 after which the mold is filled with molten glass so as to provide the body 3. After the glass is solidified the plate 4 with its surrounding body 3 of glass is placed in a mold as shown in Figure 85 6 and occupies part of the opening 11 into which the molten metal is poured when casting the casing of the engine.

The mold 5 may be smooth if desired but preferably it is formed with a number of notches 13 in which are placed cross bars or plates 14 which are preferably reduced 90 or notched so as to provide reduced extensions 15 and 16. When the bars or plates 14 are arranged in the notches 13 they rest against the plate 4 so that when the glass 3 is poured into the mold, these bars or 100 plates will be imbedded but will project beyond the glass body 3 and will, consequently, have their ends or reduced portions 15 and 16 imbedded in the casing 1 in the finished product. This construction and arrangement of cross bars 14 will make it extremely difficult, if not impossible, for anyone to 105 remove the plate 4 without detection. The

bars 14 could be made to extend across all or certain of the figures but without obliterating the same.

In Figure 6, the construction is intended 5 to represent a mold for casting the bottom part of the crank casing and when the mold is poured into the opening 11 it will flow around the plate 4 and the filling 3 of glass as it fills said opening 11. When the casting 10 is removed from the mold, the members 3 and 4 will be imbedded as shown in Figures 1 and 2, and consequently, the number plate is substantially proof against any 15 changing without mutilation. If desired, instead of casting the glass body 3 first, a sand core 12 could be formed on the plate 4 as shown in Figure 7 and this core and the plate mounted as shown in Figure 6. After the crank casing has been cast, the 20 core 12 must be removed and molten glass poured into the cavity.

In either method of manufacture, the result will be the same as shown in Figures 1 and 2, namely, the provision of a number 25 plate having parts thereof imbedded in the casting and the remaining parts surrounded by a transparent covering body.

What I claim is:—

1. An unchangeable motor number, comprising a number plate having parts thereof imbedded in the motor, and transparent means enclosing the remaining parts.
2. A device of the character described, comprising a number plate embedded in a motor casing, and a body of glass surrounding part of the number plate.
3. A motor number plate, comprising a strip of metal having a legend thereon, the strip having a portion embedded in a motor casing, and a body of transparent protecting material surrounding that part of said strip of metal having said legend thereon.
4. In a number plate for motors, the combination with a motor provided with a depression, of a transparent filling for said depression, and a number plate extending through said filling and with the ends imbedded in the motor.
5. The combination with a motor having a depression in the casing thereof, of a number plate having a legend thereon arranged with the ends of the number plate imbedded in the casing, a bar extending across said depression between the top and bottom thereof, and a transparent casting surrounding the body of said plate and substantially filling said depression.
6. In a number plate for motors, the combination with a motor provided with a depression, of a number plate extending through said depression and with the ends imbedded in the motor.
7. In a number plate for motors, the combination with a motor, of a number plate

positioned with its ends imbedded in the 65 motor.

8. In a number plate for motors, the combination with a motor, of a number plate positioned with its ends imbedded in the motor, and a protecting bar extending across 70 said plate.

9. In a number plate for motors, the combination with a motor, of a number plate positioned with its ends imbedded in the motor, and a plurality of protecting bars 75 extending across the number plate.

10. In a number plate for motors, the combination with a motor provided with a depression, of a number plate having its ends imbedded in the motor and extending 80 across the depression between the top and bottom thereof, and a protecting bar extending across the depression and over the number plate.

11. In a number plate for motors, the 85 combination with a motor provided with a depression, of a number plate extending through said depression and with the ends imbedded in the motor, and guarding cross bars extending from one part of the motor 90 to the other across said depression.

12. In a number plate for motors, the combination with a motor provided with a depression, of a number plate extending across said depression between the top and 95 bottom thereof, said number plate having its ends imbedded in the motor, said number plate having legends thereon for indicating the number of the motor, and a plurality of bars extending across said plate with the 100 number part of the bars extending into the depression, said bars being arranged so as not to obscure said legend.

13. In motor protective apparatus, the combination of a section of motor, a legend 105 embedded therein, and a guard arranged exteriorly of the legend.

14. In motor protective apparatus, the combination of a section of motor, a legend embedded therein, and a guard arranged exteriorly of the legend, the guard being also 110 embedded in said motor.

15. In motor protective apparatus, the combination with a section of motor provided with a cavity, of a legend member 115 positioned in said cavity and having part thereof embedded in said section.

16. In motor protective apparatus, the combination of a section of motor provided with a cavity, of a legend member projecting from said motor section into said 120 cavity.

17. In motor protective apparatus, the combination of a section of motor provided with a cavity, of a legend member projecting 125 from said motor section into said cavity, and a guard extending across said cavity.

LOUIS P. TERHAAR.
